UNITED STATES PATENT OFFICE.

EVA M. BOWYER, OF CHICAGO, ILLINOIS.

SUPPORTING DEVICE.

SPECIFICATION forming part of Letters Patent No. 702,398, dated June 17, 1902.

Application filed June 15, 1901. Serial No. 64,754. (No model.)

To all whom it may concern:

Be it known that I, EVA M. BOWYER, a citizen of the United States, and a resident of Chicago, in the county of Cook and State of Illinois, have invented certain new and useful Improvements in Supporting Devices; and I do hereby declare that the following is a full, clear, and exact description thereof, reference being had to the accompanying drawings, and to the letters of reference marked thereon, which form a part of this specification.

This invention relates to improvements in supporting devices, and more particularly a supporting device designed to afford attachment for an article to an article of apparel, such as a belt or the like.

The device while useful for many other purposes is herein shown as a means for attaching an umbrella to the person, thereby permitting the wearer, if a lady, to care properly for her skirts when in cars, on crowded streets, or in stores or the like. Heretofore owing to the lack of some simple and inexpensive means for attaching the umbrella to the person when not in use such articles have been frequently laid down while shopping or in cars and as a result have been lost.

The object of this invention is to provide a cheap, simple, durable, and attractive hanger adapted to be adjustably secured upon a lady's belt and adapted to permit an umbrella, parasol, or other desired article to be secured thereto, thereby leaving the hands of the user free.

The invention consists of the matters hereinafter described, and more fully pointed out and defined in the appended claim.

In the drawings, Figure 1 is a view showing a device embodying my invention applied to a lady's belt as the same may ordinarily be worn. Fig. 2 is an enlarged view of the same, showing the shade or umbrella in dotted lines. Fig. 3 is a view of the hanger, showing the same detached from the belt and in its open position.

As shown in said drawings, A indicates a belt adapted to be worn about the waist in a familiar manner.

B indicates a hanger, of leather or other suitable material, which may be cut or formed to a desired attractive shape and which is adapted at its upper end to be secured on said belt.

As shown, a glove-button of familiar type is used to afford such attachment, one member of which, b, is secured intermediate of the upper end and the middle of the hanger and the other or complementary member b' is attached near the upper end of the hanger, so that when the upper end of the hanger is passed upwardly within the belt and bent over, as shown in Fig. 2, the complementary parts of said glove-button are brought into engagement, thereby acting to secure the hanger on the belt. Obviously, if preferred, one of the members of said glove-button may be secured upon the belt itself and the other at the extremity of the hanger. Permanently secured on said hanger transversely thereof are the straps C C', the ends of which extend on opposite sides of the hanger, as shown in Fig. 3, and which are adapted to be brought around the article desired to be secured on the hanger and to be secured each to each. Obviously several different means may be employed for securing the ends of said straps together. As shown, however, glove-buttons of any desired type are used, the complementary members c c' of which are secured at opposite ends of each strip, as shown in Fig. 3, so that when said ends are brought together, as shown in Fig. 2, a slight pressure acts to close said buttons and to secure the article to the hanger. Said straps C C' are preferably of elastic material, such as rubber webbing or the like, though, if preferred, leather or other material may be used.

The operation of my invention is as follows: When the umbrella, shade, or other article is not in use, the same is laid in the position indicated in Fig. 1 and in dotted lines in Fig. 2, and the straps or bands C C' are brought around and secured tightly about the same, thereby acting to hold the umbrella or other article firmly therein and leaving the hands of the wearer or user free. Should it be desired to use the article, the same may immediately be released from the hanger and, if preferred, the hanger detached from the belt and placed in a pocket or elsewhere. Ordinarily, however, the same may be retained upon the belt in position to return the article thereto when desired. If preferred, the hanger may be permanently attached on the belt.

Obviously many details of construction may be modified without departing from the principle of this invention.

I claim as my invention—

- 5 As an article of manufacture, a relatively broad strap of flexible material, one end thereof being adapted to depend over a belt or the like and provided with glove-buttons for fastening the same thereon and having near its
- 10 other end a plurality of elastic straps or bands having the ends thereof projecting on opposite margins of the strap and having comple-

mental fastening means on the ends thereof, said strap being materially reduced in width at the point of connection therewith with said 15 elastic straps.

In witness whereof I have hereunto subscribed my name in the presence of two subscribing witnesses.

EVA M. BOWYER.

In presence of—

C. W. HILLS,
L. J. DELSON.
